Primary Examiner — Barbara Fox*Assistant Examiner* — Lilyana Bekic(74) *Attorney, Agent, or Firm* — Merchant & Gould P.C.(57) **CLAIM**

We claim the ornamental design for an inhaler, as shown and described.

DESCRIPTION

FIG. 1 is a perspective view of an inhaler showing our new design in a closed configuration;

FIG. 2 is a top plan view thereof;

FIG. 3 is a bottom plan view thereof;

FIG. 4 is a left side elevational view thereof;

FIG. 5 is a right side elevational view thereof;

FIG. 6 is a front elevational view thereof;

FIG. 7 is a rear elevational view thereof;

FIG. 8 is a perspective view of the inhaler of FIG. 1 in an open configuration;

FIG. 9 is a bottom plan view thereof;

FIG. 10 is a top plan view thereof;

FIG. 11 is a left side elevational view thereof;

FIG. 12 is a right side elevational view thereof;

FIG. 13 is a rear elevational view thereof; and,

FIG. 14 is a front elevational view thereof.

The dot-dash-dot broken lines represent the boundaries of the claimed design and form no part thereof. The dash-dash broken lines illustrate portions of the inhaler that form no part of the claimed design.
